COMBINED NAIL NIPPERS AND CLASP KNIFE

Albert M. Baer, New York, N. Y., assignor to Imperial Knife Company, Inc., Providence, R. I., a corporation of Rhode Island

Application October 1, 1954, Serial No. 459,672

2 Claims. (Cl. 30—123)

This invention relates to a combined nail nippers and clasp knife.

It is an object of the invention to provide a combination tool of the character described having a knife blade handily, compactly and foldably mounted in the handle of a nail nippers without noticeably increasing the size of the nippers so that a clasp blade is conveniently carried in this ubiquitous manicuring implement.

It is another object of the invention to provide a combination tool of the character described in which the blade is so mounted in the nippers that it will not interfere with the nail-trimming operation.

It is a further object of the invention to provide a combination tool of the character described in which the blade is protected and its cutting edge concealed when closed.

Other objects of the invention in part will be obvious and in part will be pointed out hereinafter.

My invention accordingly consists in the features of construction, combinations of elements and arrangements of parts which will be exemplified in the device hereinafter described and of which the scope of application will be indicated in the appended claims.

In the accompanying drawings in which is shown one of the various possible embodiments of my invention,

Fig. 1 is a perspective view of the combination tool with the nippers and knife blade idle, the knife blade being shown extended in dot-and-dash lines;

Fig. 2 is a view similar to Fig. 1, but illustrating the nipper actuating lever in operative position;

Fig. 3 is a sectional view taken substantially along the line 3—3 of Fig. 1;

Fig. 4 is a view similar to Fig. 3, but illustrating the knife blade in extended position;

Fig. 5 is a sectional view taken substantially along the line 5—5 of Fig. 4; and

Fig. 6 is an enlarged sectional view taken substantially along the line 6—6 of Fig. 3.

Referring now in detail to the drawings, the reference numeral 10 denotes a tool constituting a combined nail nippers and clasp knife. Said tool includes two elongated leaves 12, 14 of metallic spring stock, e. g. steel, which run from the rear 16 to the front 18 of the tool. Conveniently, the leaves have substantially identical configurations and their edges are in registration.

Intermediate the two leaves there is disposed an elongated strip 20 of resilient metal stock hereinafter referred to as the "back spacer." The back spacer extends longitudinally from adjacent the rear of the tool to near the front thereof. Means is provided suitable to secure the back spacer to one or the other of the leaves, e. g. the leaf 12, along the forward half only of the spacer. For this purpose, I provide two rivets 22 which extend through pairs of registered openings in the back spacer and leaf 12. One of these rivets is located near the front end of the back spacer and the other near the center. Thus, the rear half of the back spacer is left free and can be flexed relative to the front half.

2

For the sake of appearance, one longitudinal edge of the back spacer runs parallel to one set of registered longitudinal edges of the leaves, this edge of the spacer either being in registry with said set of edges of the leaves or inset slightly therefrom as shown in Figs. 3, 4, and 6.

A pivot such as a pin 24 extends through registered openings 26 in the leaves adjacent the rear ends thereof. The central portion 28 of the pin is of cylindrical transverse cross-section and has a diameter in excess of a transverse dimension of the portions of the pins passing through the openings 26 whereby to form shoulders 30 at opposite ends of said central portion against which the leaves bear.

The length of the central portion from shoulder to shoulder is equal to the thickness of the back spacer 20 so that when the ends of the pin engage the leaves, a compartment 32 is provided between the leaves alongside the back spacer. The compartment opens at the side of the nippers remote from the back spacer.

The ends of the pin are suitably secured to the leaves in such fashion that the leaves cannot experience angular movement with respect to one another about the pin and cannot move relative to the pin adjacent their rear ends. For this purpose, I include counter-sunk indentations 34 in the exposed surfaces of the leaves around the openings 26. The pin is headed at both ends for reception in said counter-sunk indentations. The indentations are of non-circular outline and the headed portions of the pin snugly fit in the indentations whereby the leaves are unable to rotate with respect to the pin.

A conventional knife blade 36 is disposed in the compartment 32. Said blade runs longitudinally of the compartment with its cutting edge 38 alongside the back spacer and slightly spaced therefrom when the blade is in closed position. The blade also includes a conventional tang 40 having flat parallel broad surfaces and a through aperture 42. The central portion of the pin 24 extends through the aperture 42 which thereby acts as a pivot for the knife blade. The blade thickness is almost equal to the length of the central portion of the pin so that the blade is free to rotate about the pin.

The rear end 44 of the tang is straight. The upper and lower edges 46, 48 of the tang likewise are straight, and are approximately perpendicular to the rear edge 44. The distance from the pin to each of said edges 44, 46, 48 is substantially the same and is somewhat greater than the distance from said pin to the nearest portion of the back spacer 20 when the spacer is relaxed.

When the knife is in closed position as shown in Fig. 3, it will be held there by pressure of the back spacer against the flat edge 46. Similar pressure against the edge 44 will maintain the knife in half-open position against accidental displacement; and the same action against the edge 48 will maintain the blade in the fully open position shown in dot-and-dash line in Fig. 1 against the accidental closing movement. The pressure described also will tend to bias the knife blade into any one of the mentioned position as that position is approached.

The corners 50 at the ends of the rear edge 44 are rounded to facilitate opening and closing movement of the blade.

A shoulder 52 between the edge 48 and the blunt back edge 54 of the blade is adapted to abut against the rear edge 56 of the back spacer when the blade is in fully open position (see Fig. 4).

By virtue of the foregoing arrangement the blade, when in folded, i. e. closed, position, lies substantially flat against the leaf 12 to which the back spacer is permanently secured. As is best seen in Fig. 5, the leaf 12 is substantially straight and is so maintained by the back spacer. The leaf 14 is bowed in a direction away from the leaf 12 so that when idle (relaxed), the forward por-

tion of the leaf 14 is spaced from the corresponding portion of the leaf 12 although their rear ends are held against the blade by the pin 24.

A post 58 extends through an opening 60 in the forward portion 18 of the leaf 12. Said post has an enlarged head 62 which is adapted to engage the outer surfaces of the leaf 12. The post also extends through an opening 64 in the leaf 14, said opening being somewhat larger than the diameter of the post whereby to permit flexing movement of the leaf 14 about its anchor point on the pin 24. The post includes a side opening notch 66 having an upwardly extending undercut 68 located below the upper leaf 14 when said leaf is relaxed.

The nippers is manipulated by a conventional actuating lever 70 including a head 72 and a handle 74 that are at an obtuse angle with respect to one another. The head is perforated to form an opening 76 defining a bar 78 across one edge of the head. The opening passes a portion of the tip of the post. The bar is caught in the undercut 68 and thereby maintains the leaf 14 in depressed condition.

When the lever is idle as shown in Fig. 1, the undersurface of the head faces the leaf 14. To render the lever operable it is turned 180° about the bar 78 and 180° about the post 58 to place it in the actuating position shown in Fig. 2. In such position the previously outer surface of the head rests against the leaf 14 and the handle angles outwardly away from said leaf so that when depressed it will flex the upper leaf toward the lower leaf.

The forward portions 18 of the leaves have tips 80 which are shaped to form nipping jaws of a well known type.

It will be observed that the blade is conveniently concealed between the two leaves when in closed position and thus does not interfere with the flexibility of the leaf that is operated by the actuating lever. However, when the blade is opened, the two leaves form a sturdy handle for manipulation of the blade.

It thus will be seen that there is provided a device which achieves all the objects of my invention and is well adapted to meet the conditions of practical use.

As various possible embodiments might be made of the above invention, and as various changes might be made in the embodiment above set forth, it is to be understood that all matter herein described, or shown in the accompanying drawings, is to be interpreted as illustrative and not in a limiting sense.

Having thus described the invention, there is claimed as new and is desired to be secured by Letters Patent:

1. A combined nail nipper and clasp knife tool comprising a first elongated nipper leaf, a second elongated nipper leaf, said nipper leaves having nipper tips at their forward ends, an elongated resilient back spacer between said leaves and running parallel thereto and with said leaves defining a narrow compartment, means securing the front portion only of the back spacer to the first leaf and leaving the rear end portion of the back spacer free to flex, a pin extending through said leaves adjacent the rear ends thereof and securing said leaves to one another, means to restrain the leaves against rotation relative to the axis of the pin, said last named means constituting openings in the leaves receiving the ends of the pin, said openings and ends of the pin being of matching noncircular cross section, at least said second leaf being resilient, manually manipulatable means to flex the second leaf toward the first leaf, and a clasp blade having an apertured tang rotatable on said pin and bearing against said back spacer.

2. A combined nail nipper and clasp knife tool comprising a first elongated nipper leaf, a second elongated nipper leaf, said nipper leaves having nipper tips at their forward ends, an elongated resilient back spacer between said leaves and running parallel thereto and with said leaves defining a narrow compartment, means securing the front portion only of the back spacer to the first leaf and leaving the rear end portion of the back spacer free to flex, a pin extending through said leaves adjacent the rear ends thereof and securing said leaves to one another, said pin including means to hold the leaves apart a distance substantially equal to the thickness of the back spacer, at least said second leaf being resilient, manually manipulatable means to flex the second leaf toward the first leaf, and a clasp blade having an apertured tang rotatable on said pin and bearing against said back spacer.
